[57] CLAIM

An ornamental design for a disk cartridge and/or drive, as shown and described.

DESCRIPTION

FIG. 1 is a perspective view of the disk cartridge and/or drive;

FIG. 2 is an exploded perspective view of the disk cartridge and/or drive of FIG. 1;

FIG. 3 is a top plan view of the disk of FIGS. 1 and 2;

FIG. 4 is a bottom plan view of FIG. 3;

FIG. 5 is a front elevation of FIG. 3;

FIG. 6 is a rear elevation of FIG. 3;

FIG. 7 is a right side elevation of FIG. 3, the left side elevation being a mirror image;

FIG. 8 is a top plan view of the drive shown in FIGS. 1 and 2;

FIG. 9 is a bottom plan view of FIG. 8;

FIG. 10 is the right side elevation of FIG. 8;

FIG. 11 is a left side elevation of FIG. 8;

FIG. 12 is the front elevation of FIG. 8; and

FIG. 13 is the rear elevation of FIG. 8.
